UNITED STATES PATENT OFFICE.

JOSEPH J. SZEPE, OF PITTSBURGH, PENNSYLVANIA.

WINDOW-SILENCER.

1,329,938.

Specification of Letters Patent.

Patented Feb. 3, 1920.

Application filed May 24, 1918. Serial No. 236,380.

To all whom it may concern:

Be it known that I, JOSEPH J. SZEPE, a citizen of the United States, residing at Pittsburgh, in the county of Allegheny and 5 State of Pennsylvania, have invented new and useful Improvements in Window-Silencers, of which the following is a specification.

This invention relates to an attachment 10 for windows whereas the window will be prevented from rattling and has for its primary object to provide a device of simple construction which may be manufactured in large quantities at a relatively low cost.

15 An object of the invention is to provide a window silencer that may be stamped from sheet material thus reducing the cost thereof.

Besides the above my invention is distinguished 20 in the manner of forming the rib so as to accomplish a wedging action between the window and the frame by the gravitational action of the device.

With these and other objects in view the 25 invention will be better understood from the following detailed description taken in connection with the accompanying drawing wherein:

Figure 1 illustrates a portion of a window 30 showing my invention applied thereto.

Fig. 2 is a plan view of one of the devices.

Fig. 3 is an edge view thereof.

Fig. 4 is a sectional view.

As clearly shown in Fig. 2 each device is 35 stamped from sheet material of uniform thickness of semi-disk shape with an opening 1 arranged adjacent the straight edge 2. Thus it will be seen that the major portion of the plate is arranged to one side of the 40 pivotal screw 3 that passes through the opening 1 with a result that the plate at all times tends to move to a position where the straight edge 2 is horizontally disposed. The advantages of this action will be better 45 set forth later.

In stamping the device the finger grip 4 is bent at right angles to the plate and a tapering rib 5 is formed concentrically of the opening 1. As clearly shown in Fig. 4 50 this rib is of an arcuate shape in cross section for allowing the same to be readily stamped by a stamping machine and fur-

ther insuring a good grip between the rib and the window frame. At this point I wish to call attention to the fact that although 55 the rib is shown with a plain surface the same may be corrugated or roughened so as to increase the gripping effect between the rib and the window frame. By constructing the device as illustrated and mounting 60 the same upon the window frame as illustrated in Fig. 1, it will be seen that when the devices are once forced to applied position between the window and its frame the same will be prevented from working loose owing 65 to the fact that the gravitational action of the plate will always move the rib 5 in a direction to increase the binding action between the window and its frame.

An important feature of my invention is 70 the construction of the device and its co-operation with the window and frame whereby the binding action between the frame and window will be increased to a degree to prevent raising of the window 75 should a person endeavor to raise the latter when the device is in opposite position.

From the foregoing description taken in connection with the accompanying drawing it should be apparent that I provide a device 80 of simple substantial construction which may be manufactured at a relatively low cost and which is of a shape to automatically move to a position to prevent rattling 85 of the window.

Having described my invention, what I claim is:

A device adapted to be pivotally secured to a window sash so as to engage between the sash rail and a window frame, formed 90 from a piece of sheet metal of substantial semi-circular outline provided with a pivot receiving opening positioned substantially centrally of its straight edge, said piece of sheet metal being further provided with an 95 outwardly projecting integral rib of concavo-convex cross section concentric with said opening and tapering in height toward one end, the rib acting due to its inherent resiliency to hold the device securely between the sash rail and window frame so as to effectually prevent looseness thereof.

In testimony whereof I affix my signature.

JOSEPH J. SZEPE.
